US0D1016078S

(12) **United States Design Patent** (10) Patent No.: **US D1,016,078 S**
(45) Date of Patent: ** Feb. 27, 2024

(54) **DISPLAY SCREEN OR PORTION THEREOF HAVING A GRAPHICAL USER INTERFACE**

(71) Applicant: **Stryker Corporation**, Kalamazoo, MI (US)

(72) Inventor: **Jose Daniel Martinez Galan**, Redmond, WA (US)

(73) Assignee: **STRYKER CORPORATION**, Kalamazoo, MI (US)

(**) Term: **15 Years**

(21) Appl. No.: **29/756,830**

(22) Filed: **Oct. 30, 2020**

(51) LOC (14) Cl. **14-04**

(52) U.S. Cl.
